EDWARD WADHAMS, OF YORKVILLE, NEW YORK, ASSIGNOR TO HIMSELF
AND A. WADHAMS, OF THE SAME PLACE.

Letters Patent No. 78,032, dated May 19, 1868; antedated December 28, 1867.

IMPROVED METALLIC TAG FOR STRAPS.

The Schedule referred to in these Letters Patent and making part of the same.

TO ALL WHOM IT MAY CONCERN:

Be it known that I, EDWARD WADHAMS, of Yorkville, in the county of New York, and State of New York, have invented a new and useful Metallic Tag for Straps; and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured to me by Letters Patent.

This invention relates to a metallic tag or tip for straps, such, for instance, as skate-straps, harness-straps, and the like, which are frequently buckled and unbuckled, and are very liable to have their ends turned or coiled up and frayed out, so as to render it difficult to insert them through the loops of the straps.

The invention consists in encasing the end of the strap within a thin strip of sheet metal, as hereinafter fully shown and described, whereby the end of the strap is preserved and rendered capable of always being readily passed through the loop, and retained in proper shape. In the accompanying sheet of drawings—

Figures 1 and 2 are opposite side views of the end of a strap.

Figure 3, a detached view of the metallic tag for the same.

Figure 4, an edge view of the strap with the metallic tag upon it.

Similar letters of reference indicate like parts.

The strap A, to which the invention is applied, is of the usual construction.

The tag B is constructed of thin sheet metal, brass will probably be most generally used, or a width equal to that of the strap, and of sufficient length to admit of being doubled and lap over the end of the strap, a suitable distance at either side.

The tag near one end has two rectangular openings a a, cut in it, three sides being cut to form the openings, and the strips b formed by the cuts, are bent inward, as shown clearly in fig. 3, to pass through perforations c c, made in the tag near its opposite end.

The tag is fitted over the end of the strap A, and the strips b are passed through holes in the strap, and through the perforations c c, and then clinched, as shown in fig. 1, the bend at the outer end of the tag being compressed so as to form a thin end, as shown in fig. 4.

This tag may be constructed at a very small cost, and will prove a great acquisition for all straps which are frequently buckled and unbuckled, preserving the ends of the straps, and facilitating the insertion of them through their loops.

Having thus described my invention, I claim as new, and desire to secure by Letters Patent—

As a new article of manufacture, a tag for straps, consisting of the metallic plate B, when provided with the two rectangular openings a, and strips b, and adapted to be bent over the end of the strap, as herein set forth for the purpose specified.
